(57) **CLAIM**

The ornamental design for an automotive radar, as shown and described.

DESCRIPTION

FIG. 1 is a front, top and right side perspective view of an automotive radar showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a cross-sectional view along line 8-8 of FIG. 2 thereof.

The broken lines illustrate portions of the automotive radar that form no part of the claimed design.

1 Claim, 8 Drawing Sheets
